DESIGN FOR AN ELASTIC FABRIC

Edgar Cosman, New Bedford, Mass.

Application June 12, 1940, Serial No. 92,950

Term of patent 3½ years

To all whom it may concern:

Be it known that I, Edgar Cosman, a citizen of Switzerland, residing at New Bedford, in the county of Bristol and State of Massachusetts, have invented a new, original, and ornamental Design for an Elastic Fabric, of which the following is a specification, reference being had to the accompanying drawing constituting a part thereof.

Fig. 1 is a front elevation of an elastic fabric showing my new design;

Fig. 2 is an edge elevation thereof; and

Fig. 3 is a rear elevation thereof.

I claim:

The ornamental design for an elastic fabric, substantially as shown and described.

EDGAR COSMAN.
